ATTORNEY

WITNESS:

UNITED STATES PATENT OFFICE.

JAMES B. VAN HOOSE, OF SPRINGFIELD, MISSOURI.

LOCKED EXHAUST VALVE.

Application filed July 28, 1922. Serial No. 578,182.

To all whom it may concern:

Be it known that I, JAMES B. VAN HOOSE, a citizen of the United States, residing at 948 North Main Ave., Springfield, in the county of Greene and State of Missouri, have invented new and useful Improvements in Locked Exhaust Valves, of which the following is a specification.

The object of this invention is to provide particular means for locking a valve in the exhaust pipe of the engine of a motor car, so that the engine cannot be operated until the lock is released by means of a key and the valve opened by manipulation of the controlling device of the valve.

A further object is to provide a particular form of housing, or casing, for the valve, and to provide for the mounting thereof in a particular manner so that the casing cannot be removed by detaching the securing devices therefor without first releasing the lock.

A still further object is to provide a casing for connection with an exhaust pipe, a valve and valve stem to be mounted in the casing, and a securing device in the form of a cylinder lock of the Yale type, to be opened by a key before a controlling knob can be located for rotating the stem and opening the valve in the exhaust pipe.

With the foregoing and other objects in view, the invention consists in the novel construction and arrangement of elements hereinafter described and claimed, it being understood that modifications may be made within the scope of the claim without departing from the spirit of the invention.

Fig. 1 is a plan view of my lock valve.

Fig. 2 is a longitudinal section.

Fig. 3, is a side elevation with parts broken away.

In carrying out the invention, I provide a housing or casing, designated 10, and formed with an upper portion 11 providing a chamber 12, for the reception of the locking mechanism. The body portion of the casing is provided with a bore 13 accommodating the valve stem 14, and this portion is provided with ribs or flanges 15 to facilitate radiation.

The lower portion 17 of the casing is likewise provided with ribs or flanges 15, and with a bore 18 extending at right angles to the bore for the stem. A plate or valve member 19 is carried by the stem 14 and

serves to close the bore 18, when the exhaust pipe with which the valve casing is connected is to be closed, in order to prevent the operation of the engine. A section of the exhaust pipe is designated 21, and the casing element 17 is split as shown at 22 and is provided with ears 23, through which bolts, such as 24, may pass, for clamping the element 17 to the exhaust pipe. It will be observed that the casing forms a substantially T-shaped member.

In order to rotate the stem and valve, I provide a knob 25 having thumb members 26, and also having a central recess 27 receiving the operative members of the lock. The recess just referred to is closed by a hinged cover 28.

The housing includes a flange 31 connected by means of screws 32 to the flooring 33 of the car. The screws may be inserted through openings 34 in the element 25 when the valve is in open position, and when the valve 19 is closed and is secured by the lock, the heads of the screws are beneath the plate portion of the element 25 and cannot be reached by a screw driver.

The cylindrical body 35 of element 25 is received by the recess or chamber in the member 11, and is provided with an annular groove 36 engaged by a spring pin 37, the latter acting to hold the body 35 permanently in position.

The locking pin 38 cooperates with the pin 39, in the usual manner of locks of the Yale type. The spring for element 38 is designated 40, and spring plugs are shown at 41 and 42, these plugs being retained by a plug lock pin 44, the latter being protected by the plate portion of the element 25.

When the locking elements 38, 39 are in release position, due to the insertion of a key, and the rotation of cam element 45 by cylinder 46, the body 35 may be rotated manually by the knob 25, thereby imparting rotation to the stem 14 through the connection 48, the rotation of the stem acting to open the valve 19, so that the exhaust pipe is free, and the engine may be operated.

What is claimed is:—

The combination with a valve casing for connection with a pipe, of a valve in the casing controlling the passage of fluid through the pipe, a stem for the valve, said casing having a chamber therein and including an

upper outwardly extending flange, a rotatable member within the casing for operating the stem, said rotatable member including a flange overlying the other flange, a lock for retaining said rotatable member against movement, and means positioned under the overlying portion of the flange of the ro-

tatable member for securing the casing to a stationary element, said means being non-removable when the lock is in engaging position. ¹⁰

In testimony whereof I affix my signature.

JAMES B. VAN HOOSE.
